UNITED STATES PATENT OFFICE.

CHARLES E. WERLE, OF PHILADELPHIA, PENNSYLVANIA, ASSIGNOR TO GEORGE A. REACH, OF PHILADELPHIA, PENNSYLVANIA.

ATHLETIC GLOVE.

Application filed May 22, 1925. Serial No. 32,096.

My invention relates to athletic gloves and more particularly to the type known in baseball as fielder's gloves.

The invention aims to provide an improved connection between the thumb and forefinger of such gloves, whereby greater strength is secured at the point where the greatest strains occur in the actual use of the glove during play.

10 A further object of my invention is to provide a structure in which, due to the connection between the thumb and forefinger, a pocket is formed in which a ball, caught by the wearer of the glove, will be securely held, there being no tendency for the ball to slip out through the space between the thumb and forefinger.

I am aware that gloves have been provided with webs between the thumb and forefinger, but my device is a distinct advance in the art and possesses many advantages over the structures now on the market.

20 My invention is fully described in the following specification, more particularly 25 pointed out in the claims, and is clearly shown in the accompanying drawing, in which:

Figure 1 is an elevation of a glove embodying my invention.

30 Fig. 2 is a transverse section.

Fig. 3 is a detail view.

Referring to the drawing, the numeral 1 indicates a baseball glove comprising a palm portion 2, fingers 3 and a thumb 4 set into the palm portion 2. The fingers 3 and thumb 4 are made up of front and back portions 5 and 6 respectively, which have their edges turned in, a welt strip 7 being interposed between them and they being secured together by stitching passing through the in-turned edges and the welt 7 to form a seam 8. This structure is common in the manufacture of such gloves and forms per se no part of my invention.

In its preferred form my invention comprises an integral web member 9, of leather or other suitable material, having side portions 10 and 11 and integral cross members 12 and 13, the middle portion being cut away to form an irregularly shaped opening 14. The web member 9 is preferably made of double thickness and may or may not be reinforced by stitching 15 around the opening 14.

In applying my improved web to a glove, the side portions 10 and 11 of the web 9 are placed between the inturned edges of the portions 5 and 6 of the thumb and forefinger respectively, before stitching, and are then stitched into the seam 8, the cross members 12 and 13 lying across the space between the thumb 4 and forefinger 3 of the glove 1, to form a pocket into which the ball being caught will be effectively held by the cross members 12 and 13 against any tendency to slip through between the thumb and forefinger.

It will thus be seen that the glove is materially strengthened at the point most liable to give way in hard usage and its general 70 appearance and efficiency greatly increased.

Having thus described my invention, I claim:

1. In a glove having thumb and fingers formed of front and back portions seamed together, a web having elongated side portions secured in the adjacent seams of the thumb and forefinger, said web having a pair of spaced integral cross members connecting said side portions.

2. The article of claim 1 in which the web is formed of a single piece of material folded upon itself, the middle portion being cut away and the resultant opening being reinforced by stitching passing therearound.

In testimony whereof I affix my signature.

CHARLES E. WERLE.
